(57) **CLAIM**

The ornamental design for a connector shell, as shown and described.

DESCRIPTION

FIG. 1 is a first perspective view of a connector shell showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of A portion of the second perspective view thereof.

The broken lines in the drawings illustrate features of the connector shell that form no part of the claimed design.

The Dash-Dash broken lines illustrate features of the connector shell that form no part of the claimed design. The Dash-Dot broken lines in FIGS. 2 and 9 depict the boundaries of the enlargements that form no part of the claimed design.

1 Claim, 9 Drawing Sheets
